(57) **CLAIM**

The ornamental design for a double C floor lamp as shown and described.

DESCRIPTION

FIG. 1 is a front perspective view of a double C floor lamp showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view thereof;

FIG. 9 is a front perspective view thereof, showing the double C floor lamp in an open state of use;

FIG. 10 is an enlarged detail view taken from portion 10 of FIG. 2; and,

FIG. 11 is an enlarged detail view taken from portion 11 of FIG. 2.

The broken lines in the drawings depict portions of the double C floor lamp that form no part of the claimed design.

1 Claim, 11 Drawing Sheets
